UNITED STATES PATENT OFFICE.

LEON E. LA BOMBARD AND MELVIN H. SIDEBOOTHAM, OF CHELSEA, MASSACHUSETTS,
ASSIGNORS TO SPECIALTY AUTOMATIC MACHINE COMPANY, OF CHELSEA, MASSACHUSETTS, A CORPORATION OF MASSACHUSETTS.

FEEDER FOR WARPED ARTICLES.

Application filed January 18, 1926. Serial No. 81,943.

This invention relates to mechanism for separating from the bottom of a pile, singly, articles which are warped or otherwise misshapen, and transferring them to position 5 for further treatment as by assembling them in proper relationship with other articles; and the invention has particular reference to means for feeding disks, singly, from a holder or magazine and inserting them one 10 by one into end of each of a succession of tubes preparatory to a crimping or other operation to secure the disks in place to close the ends of the tubes.

Tubular or cylindrical boxes of paper 15 stock are well known. In the manufacture of such boxes heretofore it has been customary to locate the end-closing disks in the ends of the tubes by hand, the ends of the tubes being then crimped into engagement 20 with the margins of the disks. The reason for so manually locating the disks is that cardboard is seldom naturally flat and consequently disks cut therefrom tend to curl or become warped. This feature of the 25 disks, and their curved edges, has rendered it difficult to take them singly from a supply, by machinery, and to deposit them, also singly, and by machinery, just within the ends of tubes or cylinders.

30 An important object of the present invention is to provide an automatic machine for removing disks singly from a pile or stack and then depositing them just within the open ends of tubes, ready for another operation which will secure the disks in their 35 pre-determined positions. In attaining this object, an important feature of the invention is that the pile or stack of disks is supported at three marginal points one of which is adjacent to the gate or outlet of the feeder and the other two being adjacent to opposite sides of the diametrical line which includes the first mentioned point, whereby any curled or warped condition of the disks will not 45 interfere with the pushing forward of each bottom disk through the gate or outlet.

With the above-mentioned object in view, the invention consists in the construction and combination of parts substantially as 50 hereinafter described and claimed.

Of the accompanying drawings:—

Figure 1 is a perspective view of the machine.

Figure 2 represents a section on line 2—2 of Figure 3. 55

Figure 3 is a vertical side elevation or section of the machine, with the gripper jaws just about to grasp a disk.

Figure 4 is a perspective detail view of the support for the hopper member. 60

Figure 5 is a perspective detail view of the gripping and pulling mechanism.

Figure 6 is a detail side elevation, from the side opposite that illustrated by Figure 3, of the gripper when it is pulling a disk 65 toward delivery position.

Figure 7 is a view similar to Figure 6, illustrating the delivery of a disk into the end of a tube.

Figure 8 is a perspective view of the 70 gripper mechanism from the side opposite that illustrated by Figure 5, and on a larger scale, and with side plates of the mechanism removed to show the internal members.

Similar reference characters indicate similar parts in all of the views. 75

The frame of the machine includes side plates 12 (Figs. 1, 2 and 3) having bracket portions 13 in which is rigidly mounted a cross bar 14. As best illustrated by Figure 80 4, said cross bar supports the hopper for a pile of blanks which, in the particular embodiment of the invention illustrated, are supposed to be circular card-board disks. Said hopper includes three substantially 85 vertical members of which the member 15 is a flat strip having one or more vertical slots 16 through which screws 17 pass, to secure the strip to the cross bar 14 with the lower end thereof (Fig. 3) high enough to 90 provide an outlet for a single blank. Hence said strip is termed a gate strip.

The other two upright members of the hopper are rods 18 each of which is carried by a laterally curved arm 19 having a hook-shaped portion or bracket 20 mounted on the cross bar 14 in such manner that said arms and the rods 18 may be laterally adjusted or removed and replaced by others to suit the sizes or shapes of the blanks to be piled in 100 the hopper.

Spaced from the lower end of gate strip 15 to permit the passage of a single blank is a block 21 (Fig. 3) a portion of the surface of which serves as one of the three 105 points which support the pile of blanks.

Said block is adjustable vertically, as by a screw 22, in a casing 23 supported by a stud 24 (Fig. 2) projecting in from one of the side members of the frame. The other two supports for the pile are illustrated at 25 and each has a shoulder 26. They are carried by a plate 27 mounted to slide in ways 28 carried by the side walls of the frame, an adjustable stop screw 29 being provided to 10 limit rearward movement of the slide. The slide 27 is reciprocated by a cam 30 (Fig. 3) carried by shaft 31, said cam acting on a roll 32 of a lever 33 pivoted at 34 and connected by a link 35 with an ear 36 extending 15 down from the slide, a suitable spring being connected to the lever 33 to effect return movement of the slide. This mechanism provides for only the partial ejection of a bottom blank *a* past the lower end of the gate 20 strip 15 by the action of the shoulders 26 of the members 25 pushing at two points against the rear edge of the blank to forward it to position where its front edge will be taken by the jaws of the gripping and 25 pulling mechanism presently described. As illustrated by Figures 1 and 2, the front edge of the slide 27 is recessed or cut away at 37 to permit the entry to proper position of the gripper which moves inward to approach the front edge of the blank as the blank is being ejected through the gate by the slide.

The gripper mechanism is carried by a slide bar 38 (Figs. 1 and 2) mounted in a 35 guideway 39 supported by the frame and connected by a link 40 with an arm 41 of a rock shaft 42, said rock shaft having another arm 43 the end of which has a stud or roll engaged in a path cam 44 (Fig. 3) carried by 40 the shaft 31. Rigidly mounted at the end of the slide bar 38 and projecting laterally therefrom is a pin or long stud 45 (Fig. 5) which supports the gripper mechanism.

Mounted to rock on the stud 45 is a sleeve 46 having a firmly secured arm 47 provided with a pin 48 adapted to contact, when the slide bar 38 and the gripper reach extreme outer position, with a stop 49 projecting from a block 50 which is adjustably secured 50 to the outer end of a stationary bar 51 which is secured to the frame of the machine and extends parallel with the slide bar 38.

Secured to the pin or stud 45 near its end (Fig. 5) is a cam-shaped block 52, and secured to the sleeve 46 close to said cam or block, is a block 53 (Figs. 3, 7 and 8) having a rigid ledge 54 the tip of which forms the lower jaw of the gripper.

Mounted above the ledge 54 is the upper 60 jaw member 55 the portion 56 of which contacts with the tip of the ledge 54 to grip a blank. Extending beyond said portion 56 is a pair of laterally curved flat arms 57 the purpose of which will be explained herein-after. Rising from the back of the member

55 is a finger 58, said member having also a downwardly projecting lug 59 to coact with a stop 60 of the ledge 54 to limit forward movement of the upper jaw relatively to the lower jaw.

Below the ledge 54 is a shelf member 61 having a shoulder 62 at its rear end.

Projecting laterally from both sides of the member 55 and the shelf member 61 are screw-threaded pins 63 which project through holes in side plates 64 (Fig. 5) and on which nuts are mounted, whereby the two side plates serve to hold the members 55 and 61 in rigid relationship, and at the same time coact with said members in providing a space or chamber which encloses the lower jaw member or ledge 54.

A spring 65 partly mounted in a recess in the block 53 and bearing against the member 55 tends to shift the members 55 and 61, which are rigidly connected by the side plates 64, from the position illustrated by Figure 3 to the position illustrated by Figure 7, the limit of such movement being reached when the lug 59 of the member 55 contacts with the lug 60 of the ledge member 54.

A stop pin 66 (Figs. 2 and 3) projecting from a stud 67 carried by the cross bar 14 presents its tip in the path of the finger 58 of the upper jaw member for a purpose which will be explained.

Secured in the lower part of the gripper block 53 is a pin 68 (Figs. 3, 5, 6 and 7), and secured to the outer end of said pin is a latch member 69 the tip of which serves to contact with the cam block 52 for a purpose presently explained. Also secured to the pin 68 is a latch 70 the hooked tip of which is adapted to engage a shoulder 71 on the under side of the shelf member 61. A tension spring 72 connected at one end to a bracket 73 mounted on the top of the block 53 and at the other end to the latch member 69, tends to hold the latch 70 engaged with the shoulder 71.

A spring 74 (Fig. 5), coiled around the hub of the arm 47 of the rocking sleeve 46 and connected at one end thereto and at the other end to a suitable fixed point of the slide bar 38, acts to return the sleeve and its gripper members to their upper positions as soon as the slide bar 38 returns in a direction to separate the arm pin 48 from the stationary stop 49.

Power is applied to the shaft 18 by any suitable gearing and shafting as indicated in Figure 1.

In operation, the disks or other blanks to be fed are placed in the hopper the upright members 15, 18, of which are so located relatively to each other that the margin of the lower blank of the pile will rest on the three supports 21, 15, said blank bearing on nothing else as illustrated by comparing Figures 2 and 3, whereby said blank, even if consider-

ably warped, can be reliably fed as presently explained. This is because one support (21) is in line with and close to and substantially level with the bottom of the outlet or gateway, while the other two supports (25) are in line with and close to the pushing shoulders 26.

The timing of the operation of the parts of the machine is such that the slide 27 and 10 the gripper approach each other substantially simultaneously to the relative positions illustrated by Figure 3 and then retreat. The two shoulders 26 of the slide push the bottom blank through the gateway 15 to a position where the gripper can take hold 20 of it without contacting with any other blank in the pile. Just before the parts reach their inward positions (Fig. 3), the finger 58 of the upper jaw member contacts with the tip of the stop pin 66 so that, during the slight further inward movement, the upper 25 jaw rises to admit the front edge of the blank *a* to the position illustrated by Figure 3. Then the pushing slide and the gripper begin 30 their parting movements and the spring 65 closes the upper jaw down and the blank is gripped and pulled out through the gateway and is carried to a predetermined position which, with the embodiment of the invention illustrated, is above a box-tube *b* 35 mounted on a mandrel *c* (Fig. 5). In practice a succession of such mandrels arrive and stop in position to receive a succession of the disks for further joint action, but the mechanism therefor has nothing to do with the feeder herein illustrated and therefore needs no disclosure herein.

When the slide bar 38, which carries the pin or stud 45 on which the gripper is mounted, reaches its outermost position the stop 49 (Fig. 5) carried by the fixed bar 51 arrests the pin 48 of the arm of the sleeve 46 so that, during a slight further outward movement of the slide bar, the sleeve is 45 rocked on the pin 45, in opposition to the force of the spring 74. This swings the gripper down toward the position indicated in Figure 7, and the latch member 69 contacts with the cam block 52 and lowers the latch 70 from the shoulder 62 of the shelf member 61, (Fig. 3) so that the spring 65 can then slide the upper jaw member forward until the lug 59 contacts with the stop 60 of the shelf member or ledge 54. The upper jaw member 55 is projected sharply 55 beyond the tip of the ledge 54, which tip constitutes the lower jaw member, so that the blank is projected in a downwardly inclined direction into the open top of the box tube *b* (Fig. 7).

After the delivery of a blank as described, the slide bar 38 carries the gripper back to take another blank. When the said return movement begins, the spring 74 swings the

sleeve 46 and the gripper to raise the latter, 65 and then when the finger 58 again contacts with the end of the pin 66 the upper jaw member 55 and the shelf member 61 are pushed back or slid back on the ledge 53, compressing the spring 65 and re-engaging 70 the shoulder 62 behind the latch 70, so that the jaws will retain their hold of another blank until the gripper again reaches its outer and delivery position.

The term disk employed herein is not 75 intended to limit the mechanism for use in feeding articles of circular shape. The feeder is adapted to facilitate the assembling of other articles than box ends with tubular members. For instance, by altering the relative positions of the vertical members 15, 18, 80 of the hopper to engage the edges of shoe soles, such soles can be fed to assemble them with other members for ultimate treatment by other mechanism.

Having now described our invention, we claim:—

1. A feeder having a hopper for a pile of blanks, said hopper having a delivery opening and three spaced supports for the margin of the bottom blank of the pile, two of said supports being movable, and means including said two movable supports for removing the blanks singly through said opening.

2. A feeder having a hopper for a pile of blanks, said hopper having a delivery opening and three spaced supports for the margin of the bottom blank of the pile, and a reciprocating gripper for removing the blanks singly through the opening.

3. A feeder having a hopper for a pile of disks, said hopper having an outlet and three spaced supports for the margin of the bottom disk of the pile, and a reciprocating gripper for removing the disks singly through said outlet, means being provided for causing said gripper to positively deliver each disk in a pre-determined location.

4. A machine for feeding articles not reliably flat, said machine having a hopper provided with supports for three spaced marginal portions of one of a pile of the articles, a front outlet adjacent to one of said supports, and pushing means to engage the rear of said supported article.

5. A machine for feeding articles not reliably flat, said machine having a hopper provided with three uprights for engaging the edges of a pile of circular articles and having supports for three spaced marginal portions of the bottom one of said pile of the articles, a front outlet adjacent to one of said supports, and rear pushers at opposite sides of a diametrical line which includes the support adjacent to the outlet.

6. A feeder having a hopper for a pile of blanks, said hopper having an outlet to per-

- mit the passage of the bottom article of the pile, and means for partly pushing and then pulling the bottom article through said outlet.
7. A feeder having a hopper for a pile of articles, said hopper having an outlet to permit the passage of the bottom article of the pile, a slide having pushing means for partly ejecting the bottom article through said outlet, and a reciprocating gripper to complete the removal of said article.
8. A feeder substantially as specified by claim 7, the slide having a recess in its front edge.
9. A feeder having a hopper for a pile of blanks, pushing means for partly removing the bottom blank of the pile in the direction of its plane, a reciprocating carrier having means for causing it to grasp the partly re-

moved blank when the carrier is at one end of its travel, and means for effecting release of the blank when the carrier is at the other end of its travel.

10. A feeder having a hopper for a pile of blanks, pushing means for partly removing the bottom blank of the pile in the direction of its plane, a reciprocating slide having a gripper mounted to rock relatively thereto, means for causing the gripper to grasp the partly removed blank when the slide is at one end of its movement, and means for rocking the gripper downward and effecting release of the blank when the slide is at the other end of its movement.

In testimony whereof we have affixed our signatures.

LEON E. LA BOMBARD.
MELVIN H. SIDEBOOTHAM.
